LUTHER L. KNOX, OF BELLEVUE, PENNSYLVANIA, ASSIGNOR TO BLAW-KNOX COMPANY, OF PITTSBURGH, PENNSYLVANIA, A CORPORATION OF NEW JERSEY.

HOLLOW WATER-COOLED STRUCTURE.

1,282,865.

Specification of Letters Patent. Patented Oct. 29, 1918.

Application filed April 3, 1918. Serial No. 226,404.

To all whom it may concern:

Be it known that I, LUTHER L. KNOX, a resident of Bellevue, in the county of Allegheny and State of Pennsylvania, have invented a new and useful Improvement in Hollow Water-Cooled Structures, of which the following is a full, clear, and exact description, reference being had to the accompanying drawings, forming part of this specification, in which:—

Figure 1 is a plan view, partly broken away, of a structure embodying my invention, and

Figs. 2 and 3 are sectional views taken on the lines II—II and III—III, respectively, of Fig. 1.

My invention has relation to hollow water cooled structures formed of sheet metal, and capable of use for floors, bulk-heads, shields, or the like.

The object of my invention is to provide a structure of this character which can be readily made from sheet metal in relatively large sizes, and which will possess the necessary strength.

The nature of my invention will be best understood by reference to the accompanying drawings, in which I have shown the preferred embodiment thereof, and which will now be described, it being premised, however, that my invention is not limited to the particular structure shown and described, but that various changes can be made therein within the spirit and scope of the appended claims.

In these drawings, which illustrate the application of my invention to a structure capable of being used as a water cooled floor, the numerals 2 and 3 designate the two plate or sheet members of which the body of the structure is composed. The upper member 2 has its edge portions flanged downwardly, as indicated at 4, to form the side walls of the structure, these wall forming flanges being preferably welded to the edges of the bottom member 3, as indicated at 5. The structure is shown as having an internal bracing and reinforcing system which is generally similar to that described and claimed in my Patent No. 1,168,648 of January 18, 1916, 6 designating the internal strips having spaced edge portions which are welded to the bottom plate 3. Instead, however, of making the overlapping projections welded to the upper plate 2 of strip

form, they consist of separate spaced projections 7 or lug members. It will be noted that the strips 6 have spaced projections at both edges, those opposite the welded edges bearing against the other plate member. 60 Also that the lug members 7 are staggered with respect to the projections on said strips, are shorter than the width of the strips, and are narrower than the spaces between the projections on the strips. This 65 leaves spaces through which water passes through the strips, thereby reducing heat conduction through the spacers and also giving freer water circulation throughout the structure. 8 designates the key members which engage registering apertures in the strips or projectors to tie the parts together.

9 designates a water inlet pipe which enters one end of the structure at or near 75 the center thereof, and is preferably carried through to a point near the opposite end where it is provided with a discharge T 10. The water, as it is heated, finds its way back to the opposite end portion of the 80 structure where it escapes by means of the outlet connection 11. If desired, the upper member 2 may be inclined with respect to the lower member 3, so as to give the floor an inclined surface, as shown in Fig. 2. 85

To receive the pipe 9 the key members 8 are formed in separate sections inserted on opposite sides of the structure.

It will be understood that any desired number of the unit structures shown may 90 be placed side by side in one or more rows to form a floor, bulk-head, or the like; and that the size and shape of the units may be varied according to the necessity of the particular case. 95

I claim:

1. A hollow water cooled sheet metal structure, comprising separated plate members, a plurality of internal spacing and bracing strips each of which has separated 100 edge projections welded to the inner surface of one of the plate members, and a plurality of lug members welded to the inner surface of the other plate member and overlapping said strips, said strips and lug 105 members having registering openings and key members inserted through such openings, the said lug members being of less width than the spaces between adjacent edge projections whereby water circulating spaces 110

are provided between said projections, substantially as described.

2. A hollow water cooled sheet metal structure, comprising separated plate members, one of said members having a plurality of spacing and bracing strips welded thereto, and the other member having a series of spaced projections welded thereto, said projections overlapping said strips, key members inserted through the registering openings in said projections and strips, some of said key members being inserted in one edge of the structure and others from the opposite edge of the structure, and a water inlet pipe extending between the adjacent inner ends of the two sets of key members; substantially as described.
- 10 15 3. A hollow water cooled sheet metal

structure, comprising separated plate members, a plurality of internal spacing and 20 bracing strips each of which has separated edge projections welded to the inner surface of one of the plate members, and other spaced projections at their opposite edges which bear against the other plate member, 25 and a plurality of lug members welded to the inner surface of the other plate member and overlapping said strips, said lug members being staggered with respect to the projections of the strips, and key members 30 engaging said strips and lug members, substantially as described.

In testimony whereof, I have hereunto set my hand.

LUTHER L. KNOX.
